By his Attorneys,

John Anderson, Inventor:

UNITED STATES PATENT OFFICE.

JOHN ANDERSON, OF EVELETH, MINNESOTA.

DESIGN FOR A HINGE LEAF OR MEMBER.

SPECIFICATION forming part of Design No. 32,253, dated February 20, 1900.

Application filed January 2, 1900. Serial No. 177. Term of patent 14 years.

To all whom it may concern:

Be it known that I, JOHN ANDERSON, a citizen of the United States, residing at Eveleth, in the county of St. Louis and State of Minnesota, have invented and produced a new and original Design for a Hinge Leaf or Member, of which the following is a specification.

This invention relates to a new and novel design for a hinge leaf or member, and has for its object to provide such a device which shall be both ornamental and useful.

The feature of the design resides in the flat substantially-rectangular hinge leaf or member having the pair of outwardly-directed segmental projections, which are formed upon the outer side of the leaf. These projections are alined longitudinally of the leaf, adjacent to and inwardly from the inner edge thereof, and also located adjacent to the respective opposite ends of the leaf. Each projection has its inner face rounded or convexed outwardly, and its opposite outer face is flat or straight and also inclined outwardly. The common meeting edge 5 between the straight and convexed faces is sharp, overhangs the base of the projection, and extends longitudinally of the leaf. The respective opposite ends of the projection have flat faces 6, which extend at substantially right angles to the plane of the leaf and also transversely thereof.

In the drawings, Figure 1 is a perspective view of a hinge leaf or member embodying the present design. Fig. 2 is a transverse sectional view taken through one of the projections at one end of the leaf.

Corresponding parts in both figures of the drawings are designated by like characters of reference.

Referring to the accompanying drawings, 40 the numeral 1 designates the hinge - leaf, which is flat and of substantially-rectangular form.

The numeral 2 designates the respective projections, which are of segmental shape 45 and located upon the outer side of the leaf and alined longitudinally adjacent to and inwardly from the inner longitudinal edge of the leaf. Each projection has its inner face 3, next to the inner edge of the leaf, rounded 50 or convexed outwardly, and its opposite outer face 4 is flat or straight and also inclined outwardly. The common meeting edge 5 between the straight and convexed faces is sharp, overhangs the base of the projection, 55 and extends longitudinally of the leaf. The respective opposite ends of the projection have flat faces 6, which extend at substantially right angles to the plane of the leaf and also transversely thereof. 60

What is claimed is—

The design for a hinge leaf or member herein shown and described.

In testimony that I claim the foregoing as my own I have hereto affixed my signature in 65 the presence of two witnesses.

JOHN ANDERSON.
